APPARATUS FOR SCORING FLAT BODIES SUCH AS LIDS AND END CLOSURES FOR CANS AND LIKE CONTAINERS

Benno Walensky, London, England

Application June 9, 1951, Serial No. 230,742

3 Claims. (Cl. 113—15)

This invention relates to apparatus for producing scores or weakening grooves in flat plates, more especially in the lids or end closures for containers to facilitate the opening of such containers after the lids or end closures have been applied thereto.

The invention is more particularly concerned with tool component assemblies for this purpose, applied to, or for application to, a press, one of such assemblies having as the tool component a scoring knife, and the other having as the tool component a pressure or counter-pressure element provided with rolling elements to co-operate with the scoring knife in producing the score.

The invention is especially concerned with tool component assemblies of the above mentioned character as applied to a press in which one of the tool components is a rotary component, and wherein such rotary component is mounted on the lower part or bed of the press and is driven from any suitable source of power.

One principal object of the invention is, in a press equipped with tool component assemblies, as last set forth, to provide for a dwell after closure together of the two co-operating tool components on to the lid or plate to be scored, and prior to separation of said components, in operation of the press, so that the score track will be rolled by the rolling elements on the pressure or counter-pressure element for sufficient length of time to ensure the production of a satisfactory score with an even thickness of material below the score.

It is another principal object of the invention to provide roller elements for acting upon a scoring knife with a lid to be scored therebetween and a pressure plate acting upon the rollers and applying scoring force directly to the outer periphery of the roller elements. As this scoring force is balanced the load on the bearings of the roller elements, if such bearings are incorporated, is limited to any unbalance of the force and the roller elements "float" with very little bearing reaction or bearing wear. As a result the tool assembly retains its accuracy for a long period.

According to the present invention a tool component assembly having a scoring knife as the tool component, and a tool component assembly having a pressure or counter-pressure element equipped with rolling elements as the tool component are provided for application to a press, one of such assemblies, in application, being mounted on the ram of the press, and the other on the bed of the press, to co-operate with one another in operation of the press, the tool component of the assembly applied to the bed of the press being a rotary component, and means are provided for ensuring that when the co-operating tool components have closed together on to the lid or plate to be scored, in operation of the press, further relative axial movement between them is delayed, so that a dwell occurs which allows for adequate rolling of the score track by the rolling elements provided on the pressure or counter-pressure element, before the tool components separate.

Where the tool component assemblies are applied to

2

a cam-operated press, the dwell may be produced by utilising a suitably shaped operating cam for the press.

Alternatively, and also where the tool component assemblies are applied to a crank-operated press, the dwell 5 may be produced by including in either or both of the tool component assemblies, elastic means, such as one or more springs, a dash-pot bumper, air or water cushion or the like, which provide for a "give" in either or both of the tool components after they close together, so that they 10 can then move to some extent as a unit.

By pre-loading or adjusting the elastic means, the pressure between the co-operating tool components can be pre-set.

Examples of the tool component assemblies according 15 to the invention are illustrated in the accompanying schematic drawings in which to avoid duplication of the figures, the two tool components are shown in part in each component assembly figure to illustrate converse applications of the tool components.

20 In the drawings:
Figure 1 is an elevation partly in section of a tool component assembly for application to the ram of a press; the left half of the figure shows the scoring knife mounted on the ram and the right half shows the rolling elements mounted thereon to illustrate the reversibility of the two elements.

25 Figure 2 is an elevation partly in section of a tool assembly applied to the bed of a press for co-operation with the tool assembly shown in Figure 1; the left hand part of the figure cooperating with the left hand part of Figures 1, 4, 5 or 6 and the right hand part of the figure cooperating with the right hand part of Figures 1, 4, 5 or 6 to illustrate the reversibility of mounting of the scoring knife and roller elements on either the bed or the ram of 30 a press.

35 Figure 3 shows in elevation partly in section a modified form of the assembly shown in Figure 2;

Figures 4, 5 and 6 illustrate in sectional elevation three 40 alternative forms of tool assemblies for application to the ram of the press the left hand part of each figure showing the roller elements mounted thereon and the right hand portion showing the scoring knife mounted thereon.

45 In one example, the tool component assembly to be applied to the ram of the press comprises, as shown in Figure 1, a disc or plate 1 provided with a shank 2 to fit into a bore in the ram of the press, the plate 1 having attached thereto a scoring knife 3, the scoring or cutting edge of which is directed downwards. The scoring knife 3 is shaped to produce the required shape of score. In 50 the present example it is annular or circular.

The tool component assembly to be applied to the bed 55 of the press comprises, as shown in Figure 2 (left hand side) a rotary disc 4 supporting a cage or carrier 5 for rolling elements 6 such as rollers or balls and secured on a vertical driving shaft 7 which is mounted in ball or roller bearings 8 in a central bore of a non-rotary support 9 of circular cross section arranged for vertical sliding movement in a cylindrical housing 10 and urged upwards by a helical compression spring 11, which beds 60 at its lower end on a screwed plug 12 screwed into the bottom of the housing 10 and through which the driving shaft 7 passes, the housing 10 fitting in a cavity in the bed 13 of the press and having an outwardly directed flange 10' at the top, which beds on a bolster 14 mounted on the bed 13 of the press.

65 It will be appreciated that the cage 5 extends around the top of the disc 4, and carries another set or several other sets of rollers or balls 6.

70 The spring urged axially movable support 9 has an outwardly directed flange 9' intermediate of its ends, and it is reduced in diameter as at 9" below the flange.

The flange 9' is provided with ribs or keys 15 which slide in vertical guide channels 16 in the inner wall of the housing 10 to the axially movable support 9 thus being guided in its vertical sliding movement and being prevented from rotating.

The spring 11 surrounds the reduced lower end 9" of the axially movable support 9.

The rotary disc 4 is mounted on ball or roller bearings 17 on the top of the axially movable support 9.

The housing 10 is internally screw-threaded, and a ring 18, or more than one ring, is screwed into the housing 10 to form an abutment for the flange 9' on the axially movable support 9.

The ring 18 embraces the portion of the axially movable support 9 above the flange 9' thereon and so serves also to centre said support 9 and to guide its vertical movement.

The ring 18 serves also to determine the position of the rotary disc 4 in relation to the housing 10.

By screwing the ring 18 or the bottom plug 12 inwards or outwards, within the housing 10, the pressure of the spring 11 can be adjusted.

The ring 18 may be replaced by an inwardly directed rib or flange on the housing 10.

The driving shaft 7 is connected with the driving mechanism (not shown) by means of a keyed connection which permits the shaft 7 to move axially without interrupting the driving connection.

In operation, when the ram of the press descends and the scoring knife 3 and rolling elements 6 are thus brought together, with the inserted lid or plate to be scored between said knife and rolling elements, they then move together as a whole against the action of the spring 11, in the completion of the downward movement of the ram, so causing a dwell during the end of the down stroke and the beginning of the up stroke which allows the rolling elements 6 to roll over the track of the score sufficiently to ensure a satisfactory score with an even thickness of material below the score, before the pressing components separate.

A stop, which may be a ring 19, as shown on the right hand side of Figure 2, is mounted on the rotary disc 4 on which the outer rolling elements 6 abut, to predetermine the clearance between the edge of the knife 3 and the inner rolling elements 6, when the knife and rolling elements close together, so determining the thickness of the material left below the score.

This thickness may be varied by adjusting the height of the stop 19 or the extent of projection of the scoring knife 3, by means of shims for example, or by making the knife or stop adjustable by means of screw-threaded mountings.

Instead of arranging the knife 3 on the ram of the press, and the member carrying the rolling elements 6 on the bed 13 of the press, the converse arrangement can be adopted, the knife 3, in such case, then being mounted on the rotary disc 4, as shown on the right hand side of Figure 2, so that the knife is rotated.

In another example shown in Figure 3, the driving shaft 7 for the rotary disc 4 is provided with a belt pulley 20 which runs on ball or roller bearings 21 on the top of the housing 10 as shown on the right hand side of the figure, or on a ring 22 fixed in the open top of the housing 10 and bedding on an inward internal shoulder 23 thereon, as shown on the left hand side of the figure, so that the drive can be transmitted by a belt from the side of the press.

The driving shaft 7 in this example terminates short of the bottom plug 12 for the housing 10 and is provided with a collar 23 between which and a disc 24 a ball or roller bearing 25 is provided, the spring 11 bearing at its upper end against the disc 24, and having its lower portion accommodated in a cavity 26 in the plug 12 for the bottom of the housing 10.

The pulley 20 has a hollow depending hub 27 running in a bearing bush 28 fitted within the housing 10 or within the ring 22 in the housing 10 so centreing the pulley 20.

The shaft 7 has a keyed connection 29 with the pulley 20 so that the shaft can slide through the pulley without interrupting the drive.

Instead of a belt and pulley drive, a sprocket wheel and chain drive, or a geared drive can be adopted in this example.

10 As an alternative to the example previously described, the elastic means may be provided in the tool component assembly for application to the ram of the press.

In one example of such an alternative as shown in Figure 4 a helical compression spring 11 is arranged 15 within a cylindrical housing 30 which is screwed into a carrier plate 31 provided with a shank 2 to fit into a bore in the ram of the press.

The spring housing 30 is open at the bottom, and is provided, at the bottom with an outwardly directed 20 flange 30'.

A cylindrical holder 32 which is closed at the bottom is provided to support the tool element which may be the cage 5 with the rolling elements 6, as shown on the left hand side of the figure, or if preferred, the scoring knife 25 33, as shown on the right hand side of the figure, such holder 32 having an internal diameter such that it will pass freely over the bottom flange 30' on the spring housing 30.

The holder 32 is screw-threaded internally to receive 30 a screw-threaded sleeve 33.

In assembling, the spring 11 is inserted in its cylindrical housing 30, the holder 32 is slipped on to the bottom of the housing 30 so that the spring bears at the top against the closed upper end of the housing 30 and at the bottom 35 against the closed bottom of the holder 32, and the screwed sleeve 33 is screwed into the holder 32 so that its lower end bears on the bottom flange 30' of the spring housing 30.

By screwing the sleeve 33 in or out the compression 40 of the spring 11 can be adjusted.

The sleeve 33 may have a top flange 33' provided with radial holes 34 for a "Tommy bar" to facilitate its rotation.

The flange 30' on the spring housing 30 is provided 45 with ribs or keys 35 to engage slidably in vertical guide channels 36 in the inner wall of the holder 32 so that the holder is guided in its vertical sliding movement but is prevented from rotating.

The holder 32 is flat on its underside to bed the tool 50 component 6 or 3, and may be shouldered externally to facilitate attachment of the tool component.

In another example shown in Figure 5 the spring 11 is arranged externally between the carrier plate 31 fitted to the ram of the press and the holder 32 for the tool 55 component 6 or 3.

The carrier plate 31 has a downwardly depending hollow shank 31', which is a sliding fit in an upwardly directed reduced cylindrical extension 32' of the holder 32.

The spring 11 surrounds this extension 32' and bears 60 at one end against the carrier plate 31 and at the other end on a shoulder 32" formed by the reduced extension of the holder 32.

A screwed bolt 37 is passed centrally through the holder 32 and through the depending hollow shank 31' of the carrier plate 31, such shank having a closed bottom 31", with an opening formed therein for the passage of the bolt 37.

The bolt 37 screws into a nut 38 arranged within the hollow shank 31' of the carrier plate 31.

70 A recess 39 is provided in the bottom of the holder 32 to accommodate the head 37' of the bolt 37.

The nut 38 is keyed to the hollow shank 31' as at 40 to prevent said nut from rotating and the hollow shank 31' is provided with ribs or keys 41 to engage slidably 75 in vertical slots in the extension 32' of the holder 32.

so that the holder 32 can slide on the shank 31' but is prevented from rotating.

By screwing the bolt 37 in or out, the holder 32 slides axially on the hollow shank 31' so adjusting the compression of the spring 11.

More than one spring can be used.

In a further example shown in Figure 6, having a central bolt 37 screw-threaded for part of its length only from the end for adjusting the compression of the spring, the spring 11 is arranged in a housing 31' formed integrally with the carrier plate 31 and open at the lower end.

The housing 31' slides in an upwardly directed extension 32' provided on the holder 32 as in the previous example.

The spring 11 bears at its lower end on the bottom of the holder 32, within the upwardly directed extension 32' and the nut 38 is arranged within a bore 42 in the upwardly directed shank 2 of the carrier plate 31, and is keyed in said bore the bottom of which is closed but provided with an opening for the passage of the bolt.

The head 37' of the bolt 37 is accommodated in a cavity 39 in the bottom of the holder 32.

A screw cap 43 is screwed into the cavity 39 to prevent the bolt moving axially downwards should the nut 38 become jammed, the screw cap 43 having an opening 44 in its base for the passage of an operating key.

In the first two examples described adjustment of the spring loading does not alter the setting of the tool components.

While there has been presented above several embodiments of the invention, now believed to be preferred, many variations will readily suggest themselves to those skilled in the art. All these different forms which fall within the spirit of the invention are intended to be covered by the appended claims wherein generic terms are employed for the express purpose of including the many equivalent structures by which the present results may be obtained.

What I claim is:

1. In combination in a press of standard construction having cooperating bed and ram members arranged for

the automatic, large quantity production scoring of sheet metal ends for containers for standard pack canning, rotatable mounting means carried by one of said cooperating members, a first tool component assembly having a

5 scoring knife as a tool component, a second tool component assembly having roller elements as a tool component, one of said assemblies being mounted on said rotatable mounting means carried by one said cooperating member and the other of said cooperating members comprising a disc member mounted for applying scoring force to the peripheries of said roller elements.

2. In combination a tool assembly for the quantity production scoring of sheet metal closures for standard pack containers comprising a first tool component assembly having a scoring knife and stop means providing

15 a closed path element spaced from and projecting beyond the scoring edge of said knife, a second tool component assembly having roller elements with means to mount them for rotation and means providing an annular surface in rolling contact with said elements, shaft

20 means for aligning said tool component assemblies with the roller elements in rolling contact with said annular surface on one side of said elements and said closed path element diametrically opposite therefrom whereby balanced forces cause said roller elements substantially to float in the said means to mount them for rotation.

25 3. The combination set forth in claim 2, means to rotate one of said tool component assemblies with respect to the other said tool component assembly.
